US0D1042385S

(12) United States Design Patent (10) Patent No.: US D1,042,385 S
(45) Date of Patent:  *Sep. 17, 2024

(54) MOBILE ELECTRONIC DEVICE

(71) Applicant: Samsung Electronics Co., Ltd., Suwon-si (KR)

(72) Inventors: Junghyun Choi, Suwon-si (KR); Bosoon Kang, Suwon-si (KR); Byoungjin Kim, Suwon-si (KR); Tae-ho Kim, Suwon-si (KR); Junyong Song, Suwon-si (KR); Woohyeok Jeong, Suwon-si (KR)

(73) Assignee: SAMSUNG ELECTRONICS CO., LTD., Suwon-si (KR)

(*) Notice: This patent is subject to a terminal disclaimer.

() Term: 15 Years

(21) Appl. No.: 29/860,900

(22) Filed: Nov. 23, 2022

(30) Foreign Application Priority Data

May 26, 2022 (KR) 30-2022-0020977

CLAIM

The ornamental design for a mobile electronic device, as shown and described.

DESCRIPTION

FIG. 1 is a top front perspective view of a mobile electronic device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a bottom rear perspective view thereof.

The dashed broken lines in the figures depict portions of the mobile electronic device that form no part of the claimed design.

1 Claim, 8 Drawing Sheets
